UNITED STATES PATENT OFFICE.

JOHN PARKINSON, OF LOS ANGELES, CALIFORNIA, ASSIGNOR TO THE
PACIFIC ELEVATOR COMPANY, OF SAME PLACE.

SAFETY-ELEVATOR.

SPECIFICATION forming part of Letters Patent No. 556,434, dated March 17, 1896.

Application filed October 24, 1894. Serial No. 526,868. (No model.)

To all whom it may concern:

Be it known that I, JOHN PARKINSON, a citizen of the United States, residing at Los Angeles, in the county of Los Angeles and State 5 of California, have invented a new and useful Safety-Elevator, of which the following is a specification.

One object of my invention is to secure superior simplicity of construction.

10 Another object is to provide a superior safety device which is self-acting and practically instantaneous and at the same time is fully under the control of the operator in the car and can be operated to stop the car at will, 15 and which will readily act to become released when the car is reversed and started up.

Another object is to make a safety appliance absolutely positive in its action, so that the downward movement of the car will cause 20 it to instantly act the moment the speed exceeds the limit set and almost immediately stop the car.

Another object is to provide an elevator which can be operated by a slow-running 25 electric motor, thereby avoiding the noise which attends the operation of the rapid motors ordinarily necessary to give the speed for passenger-elevators.

My invention consists in various elements 30 and combinations hereinafter described and claimed.

The accompanying drawings illustrate my invention.

Figure 1 is a plan showing operative parts 35 of my improved elevator. The racks and parts of the frame are shown in horizontal cross-section, indicated by line 1 1, Figs. 2, 4, and 5. Fig. 2 is an elevation of the operative parts, looking between the guides. Fig. 3 is 40 a sectional elevation on line 3 3, Fig. 1, looking to the right. Fig. 4 is a cross-sectional elevation looking to the right in Fig. 1 from line 4 4. Fig. 5 is a sectional detail of the safety device. Fig. 6 is a sectional plan on line 6 6, Fig. 5.

My invention embraces the combination of two vertical double-faced racks A A', having 45 their bodies preferably formed of channel-iron, two rotating shafts B B', mounted on a moving frame 2 in a plane at right angles to the racks and provided respectively at their

opposite ends with the traveling pinions b b' and b¹ b¹', geared respectively in the toothed faces of the racks, the pinions of one shaft being opposite the pinions of the other shaft. 55 A suitable motor C is carried by the car, and suitable mechanism connects the motor with the shafts to drive them.

My invention also embraces the combination of a double-faced rack having its body 60 formed of channel-iron, a moving frame arranged to move along the rack, two traveling pinions mounted on the frame and arranged to mesh respectively with the opposite faces of the rack, and means for simultaneously ro- 65 tating the pinions in opposite directions.

It also embraces other features and combinations, hereinafter described and claimed.

In the drawings the guides for the opposite sides of the frame consist of the opposite racks, 70 and the pinions are geared therein.

The mechanism which is used to communicate the power from the motor C to the shafts B B' consists in the armature worm-shaft D, provided at its ends with the worms d d', the 75 cog-wheels E E', fixed upon the pinion-shafts B B' and geared with the worms d d', respectively, so that the rotation of the worms by the motor will rotate the shafts and thus cause the pinions to travel along the racks. 80

The means by which I provide for absolute safety against any objectionable fall of the elevator consists essentially in a sliding lock-screw sleeve F arranged around the pinion-shaft B and adapted to slide along and to rotate with such shaft and screw into a stationary nut or screw seat or socket G arranged to receive the sliding screw. Splines f prevent the sleeve from turning on the shaft, and suitable means are arranged to operate 90 the sliding screw-sleeve to slide it along the shaft and bring it into engagement with the screw-seat and thereby cause it to be screwed into the screw-seat. This will stop the rotation of the pinion-shaft and thereby prevent 95 the movement of the cage in the direction which screws the screw into the nut. The screw is arranged to thus lock the car against its downward motion, and governor appliances are arranged to slide the sliding screw 100 into engagement with its seat when the rapidity of the descent exceeds the desired

limit. Each pinion-shaft B B¹ is provided with a like locking arrangement. In the drawings like parts of the two locking arrangements are indicated by like reference-
5 letters. The letters which indicate parts of the locking device applied to the shaft B¹ are distinguished by an index.

The governor arrangement which I have invented consists in the rotating governor-
10 carrier II journaled to the frame by suitable means and provided with the carrier-driving cog h, the beveled wheel I geared with the carrier-driving cog h and provided with the pinion i, which meshes with the wheel J fixed
15 upon one of the pinion-shafts, B, the weighted governor-arms K K', provided respectively with segmental cogs k k', a cylinder-gear L meshing with the segmental cogs k k', the toggle-joint M M', having one of its arms M piv-
20 oted to the circular gear L and the other arm pivoted to the frame, and a connecting-rod N connecting the toggle-joint with the lock-screws F through suitable means, such as a yoke O, which embraces both screw-sleeves
25 and in which the screw-sleeves rotate freely. The yoke is connected with the screws, so as to reciprocate them axially, the screws being journaled to revolve in the yoke. One mem-
30 ber or arm, M', of the toggle-joint is fixed to the rocking shaft P, which is pivoted to the frame and is provided with the upright lever Q, by which the shaft P can be operated, thus to throw the toggle-joint member M' to operate the connecting-rod and cause the screw F
35 to engage with its nut G. The rocking shaft thus forms the pivot by which the toggle-arm M' is pivoted to the frame.

For the purpose of adjusting the governor for greater or less sensitiveness the lever Q
40 is provided with the movable part q, which is adjustable (by means of the slot q¹ and the nut and bolt q²) on the adjusting-arm q', which is fixed on the rocking shaft P. This mov-
45 able part constitutes an adjusting-weight for the governor.

The carrier II is mounted upon a suitable axle R provided with the ball-bearing r, so that the carrier will rotate freely. The axle R is hollow and forms a guide for the cylinder-gear L which reciprocates therein. The
50 axle is provided with the ball-bearing flange r', and the rotating carrier is provided with the internal ball-bearing shoulder h', which is arranged above the flange of the axle, and
55 the antifriction-balls r are interposed between the flange and the shoulder. This con-
trivance forms a superior hanging ball-bearing for the depending rotating carrier.

In practical operation the pinion-shafts B
60 B¹ are rotated, thus causing the pinions b b' to travel along the vertical racks, and also causing the governor-carrier II to rotate upon its axle. In case the car should fall the moment the speed exceeds the limit for which
65 the governor is set the weights of the gov-
ernor-arms are thrown out and up, thus, through the toothed segments, pulling down

on the cylinder-gear L and operating the toggle-joint to force the yoke O and the lock-screws F F', which it carries, toward the nuts 70 or screw-seats G G'. The moment the screws engage the seats they begin to screw thereinto at the same speed of the shafts, and as soon as seated the rotation of the shafts is stopped thereby, and consequently the car is 75 held firmly against further descent. The car is at perfect liberty, however, to be again drawn up, and when the upward movement takes place the screw is withdrawn from its socket and is only inserted again upon ex-
cessive downward speed or upon the operation of the lever Q while the car is descending. The length of the lock-screws F F' determines the length of movement of the car after the lock-screws have been started into their seats. 80 Liability of breakage is avoided by making the screws very strong and so short that they are fully seated before the car has traveled any great distance. This prevents the car 85 from gaining any serious momentum before 90 it is stopped.

By means of the combination of the depend-
ing axle R provided with the journal-shoulder r' and the rotating governor-carrier II sus-
pended upon such axle and sustained 95 thereon by the balls r, I am enabled to place the governor beneath the car in the most con-
venient position for the same.

By means of the double-faced rack and the traveling pinions b' b¹ friction between the 100 rack and the traveling pinions is very largely avoided, for the reason that the pinions thus arranged on opposite sides of the rack cause each other to mesh accurately with the rack and prevent any cramping of the bars. 105

In practice, to adjust the governor to the proper sensitiveness the upper or movable part of the lever is slid to such a position on the adjusting-arm as to sufficiently balance the weight of the weighted governor-arms 110 when the frame is moving at the desired speed, and then when such speed is exceeded the governors will readily act to reciprocate the cylinder-gear.

If it is desired to stop the cage on its down-
ward descent the lever is thrown to force the 115 screw-sleeve into its seat.

Now, having described my invention, what I claim as new, and desire to secure by Letters Patent, is—

1. The combination of a moving frame ar-
ranged to move between guides: a rack: a ro-
tating shaft mounted on the frame: a travel-
ing pinion fixed upon the shaft and arranged 120 to mesh with and travel along the rack: a
screw-sleeve arranged around the shaft and
adapted to slide along and rotate with such
shaft: a nut fixed to the frame and arranged
to receive the sliding screw-sleeve, and suit-
able means arranged to reciprocate the screw-
sleeve to bring it into engagement with the
nut. 125

2. The combination of a rotating shaft: the
sliding sleeve mounted thereon and arranged

to slide therealong and rotate therewith: a screw-seat arranged to receive such sleeve and a governor for automatically sliding the sleeve along the shaft to cause it to engage the screw-seat.

3. The combination of a moving frame arranged to move along a rack: the rack: a rotating pinion-shaft mounted on the frame: a traveling pinion fixed upon the shaft and arranged to mesh with the rack: a screw-sleeve arranged around the pinion-shaft and adapted to slide along and rotate with such shaft: a screw-seat arranged to receive the sliding screw-sleeve: a governor-carrier journaled to the frame by suitable means: a weighted governor-arm provided with a toothed segment: a cylinder-gear meshing with the toothed segment: operative means connecting the cylinder-gear with the screw-sleeve to reciprocate it along the shaft and suitable operative means connecting the shaft with the governor-carrier to rotate the same.

4. The combination of a moving frame arranged to move along a rack: the rack: a rotating pinion-shaft mounted on the frame: a traveling pinion fixed upon the shaft and arranged to mesh with the rack: a screw-sleeve arranged around the pinion-shaft and adapted to slide along and rotate with such shaft: a screw-seat arranged to receive the sliding screw-sleeve: the governor-carrier axle fixed to the frame: the governor-carrier journaled on such axle by suitable means; the reciprocating cylinder-gear mounted in the carrier-axle: the toggle-joint having one end pivoted to the frame and the other end pivoted to the cylinder-gear: the connecting-rod pivoted at one end to the toggle-joint and at the other end to the sliding screw-sleeve: the weighted governor-arms pivoted to the carrier and provided with the toothed segments meshing with the cylinder-gear: the screw-seat arranged to receive the screw-sleeve, and means for connecting the pinion-shaft with the governor-carrier to cause the rotation of the shaft to rotate the carrier.

5. The combination of a moving frame arranged to move along a rack: the rack: a rotating pinion-shaft mounted on a frame: a traveling pinion fixed upon the shaft and arranged to mesh with the rack: a screw-sleeve arranged around the pinion-shaft and adapted to slide along and rotate with such shaft: a screw-seat arranged to receive the sliding screw-sleeve: the governor-carrier axle fixed to the frame and provided at one end with the ball-bearing flange: the rotating governor-carrier mounted on such axle and provided with the interior ball-bearing shoulder arranged above the ball-bearing flange: anti-friction-balls arranged between the flange and the shoulder: the reciprocating cylinder-gear mounted in the carrier-axle: the toggle-joint having one end pivoted to the frame and the other end pivoted to the cylinder-gear: the connecting-rod pivoted at one end to the toggle-joint and at the other end to the

sliding screw-sleeve: the weighted governor-arms pivoted to the carrier and provided with the toothed segments meshing with the cylinder-gear: the screw-seat arranged to receive the screw-sleeve, and means for connecting the pinion-shaft with the governor-carrier to cause the rotation of the shaft to rotate the carrier.

6. The combination of a moving frame arranged to travel along a rack: the rack: a rotating pinion-shaft mounted on the frame: a traveling pinion fixed upon the shaft and arranged to mesh with the rack: a screw-sleeve arranged around the pinion-shaft and adapted to slide along and rotate with such shaft: a screw-seat arranged to receive the sliding screw-sleeve: a governor-carrier axle fixed to the frame and provided at one end with the ball-bearing flange: the rotating governor-carrier mounted on said axle and provided with the interior ball-bearing shoulder arranged above the ball-bearing flange: anti-friction-balls arranged between the flange and the shoulder: reciprocating cylinder-gear mounted in the carrier-axle: the rocking shaft journaled to the frame: the toggle-joint having one arm fixed to the rocking shaft and the other arm pivoted to the cylinder-gear: the connecting-rod pivoted at one end to the toggle-joint and at the other end to the sliding screw-sleeve: the weighted governor-arms pivoted to the carrier and provided with toothed segments meshing with the cylinder-gear: means for connecting the pinion-shaft with the governor-carrier to cause the rotation of the shaft to rotate the carrier: the adjusting-arm fixed to the rocking shaft, and a suitable weight adjustably mounted on such adjusting-arm.

7. The combination of a moving frame arranged to travel along a rack: the rack: a rotating pinion-shaft mounted on the frame: a traveling pinion fixed upon the shaft and arranged to mesh with the rack: the screw-sleeve arranged around the pinion-shaft and adapted to slide along and rotate with such shaft: a screw-seat arranged to receive the sliding screw-sleeve: a rocking-shaft journaled to the frame and connected with the screw-sleeve to reciprocate it along the shaft: and means for rocking the rocking shaft.

8. The combination of the rotating shaft: the screw-sleeve arranged around the shaft: the screw-seat arranged to receive the sliding screw-sleeve: a rotating governor-carrier: means for rotating the carrier: a cylinder-gear operatively connected with the screw-sleeve to slide the same along the shaft: and a weighted governor-arm pivoted to the carrier and provided with toothed segments meshing with the cylinder-gear.

JOHN PARKINSON.
